UNITED STATES PATENT OFFICE.

CARLYLE W. THOMAS, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

RUFFLING MECHANISM FOR SEWING MACHINES.

1,412,903.

Specification of Letters Patent. Patented Apr. 18, 1922.

Application filed December 9, 1919. Serial No. 343,532.

To all whom it may concern:

Be it known that I, CARLYLE W. THOMAS, a citizen of the United States, residing at Bridgeport, in the county of Fairfield and State of Connecticut, have invented certain new and useful Improvements in Ruffling Mechanisms for Sewing Machines, of which the following is a specification, reference being had therein to the accompanying drawings.

This invention relates to improvements in sewing machines for ruffling and stitching fabrics and has for its primary object to provide a mechanism of this character whereby products may be effected by a single operation that heretofore required a multiple of operations, in consequence lessening the cost of manufacture of such products and at the same time substantially enhancing the appearance of the latter.

To the attainment of the object of this invention, a plurality of ruffling blades are arranged in superposed relation in a manner such that each of the ruffling blades acts on similar sides of fabrics to be united in superimposed relation by stitching.

In the present embodiment of the invention, the ruffling blades are adapted to be simultaneously actuated to perform their ruffle-forming movements either differentially or synchronously with respect to each other, according to the adjustment of the actuating mechanism. In order to permit the ruffling blades to simultaneously act upon several fabrics, particularly in differential relationship, there is provided a separating blade intermediate the ruffling blades, upon which separating blade the upper of the ruffling blades operates to ruffle a fabric without interfering with the operation of the lower ruffling blade upon another fabric. Suitable guides are preferably provided for the different plies of material, permitting of the uniting by stitching of the ruffled fabrics with a body garment in a single operation.

In the accompanying drawings, Fig. 1 is a view in front side elevation of the front end portion of one form of commercial sewing machine embodying the present invention. Fig. 2 is a view in front end elevation of the machine as shown in Fig. 1. Fig. 3 is a view in sectional elevation of Fig. 1, looking in the direction indicated by the arrow

S. Fig. 4 is an inverted plan view taken substantially in the plane A, B, Fig. 1. Fig. 5 is a view in perspective of the cloth-presser employed. Fig. 6 is a view in perspective of the lower of the ruffling blades and its supporting mechanism. Fig. 7 is a view in perspective of the edge folder for the body-garment combined with a separating blade. Fig. 8 is a view in cross-section of the inner radially projecting lever for transmitting movements to the upper of the two ruffling members, together with an adjustable stop-block. Fig. 9 is a view partly in section of the radially projecting lever and radially projecting crank-arm for transmitting movements to the lower of the two ruffling members, together with the pivot-block and coupling. Fig. 10 is a view of the telescopically arranged ruffling blade actuating shafts. Fig. 11 is a view of one variety of product effected by the present invention.

The present invention is shown and will be described as applied to one form of Singer commercial sewing machine, but as the invention relates only to the construction and application of a multiple ruffling mechanism, only such reference will be made to the other elements of the machine as is deemed necessary for a proper understanding of its application.

Referring to the drawings, the sewing machine frame as usual includes a base 1, having the slide-plates 2 and 3, and an overhanging bracket-arm 4, unsupported at its free end. Journaled in suitable bearings provided in the overhanging bracket-arm is the main or driving shaft 5 operatively connected, in the usual manner, with the needle-bar 6 carrying the needle 7, whereby vertically reciprocatory stitch-forming movements are imparted to the latter.

Carried by the driving shaft 5 is the eccentric 8, embraced by the strap 9 on one end of a pitman 10. The opposite end of the pitman 10 is connected by means of a pivot stud 11 with a radially projecting crank-arm 12 suitably secured upon the inner end of a short shaft 13 journaled in a bearing provided in an elongated boss 14 of a bracket 15. The bracket 15 is secured by screws, as 16, upon the bracket-arm 4 and is formed with a second elongated bearing boss 17 arranged substantially parallel with the boss 14. The crank-arm 12 is permanently se-

cured to one end of a U-shaped arm 18 of which the other end carries a second crank-arm 19. The crank-arms 12 and 19 are substantially parallel and it is to be understood that by means of their rigid connection with each other, the crank-arms are simultaneously vibrated under the action of the pitman 10.

Journalized in a bearing provided by the boss 17 is a hollow rock-shaft 20 in turn forming a bearing for a rock-shaft 21 arranged telescopically within and longer than shaft 20. Secured by set-screw 22 upon shaft 20 adjacent the boss 17 is the hub of a lever 23 provided with a radially extending slot 24 arranged opposite to a groove 25 formed in the crank-arm 12. In like manner, the hub of a lever 26 is secured by set-screw 27 upon the rock-shaft 21 adjacent the end of the shaft 20 and is provided with a radially extending slot 28 arranged opposite to a groove 29 formed in the crank-arm 19. Referring more particularly to Fig. 9, there is fitted within the slot of lever 26 a flanged pivot block 30 penetrated by a pin 31 carrying at one end a slide-block 32 fitted within the groove 29 of crank-arm 19. At its opposite end, the pin 31 is threaded for the reception of a wing-nut 33 acting upon a washer 34 positioned adjacent an index-plate 35, the described construction serving to securely hold the slide-block 32 against accidental movement, but permitting the ready adjustment thereof in a manner well known. A similar connection is provided intermediate the lever 23 and crank-arm 12, the slide-block 36 being indicated by dotted lines, with the exception that a crank-pin 37 is employed instead of the wing-nut 33 to secure the slide-block 36 in adjusted position. The levers 23 and 26 are preferably each provided with an adjustable stop-block 38 secured in position by means of a screw 39, a washer 40 being interposed between the head of the screw and the lever. Secured by screws, as 41, upon the forward end of shaft 21 is a shaft crank 42 to which is adjustably attached, by screws as 43, a supporting plate 44. Pivotaly sustained on the plate 44 by pivot screw 45 is a blade-carrying lever 46, to one arm of which is suitably secured the laterally offset shank of a lower ruffling blade 47 and of which the other arm terminates in a forwardly projecting finger 48. Formed integral with the lever 46 is a finger-piece 49 provided with an elongated aperture 50 through which extends a threaded rod 51 suitably secured in a projection 52 on the supporting plate 44. Surrounding the rod 51 is a coiled spring 53 interposed between the finger-piece 49 and an adjusting nut 54 threaded upon the rod. By the adjustment of the nut 54 it is evident that the ruffling blade 47 is caused to yieldingly bear down-

wardly with the desired pressure. However, for the insertion or removal of the work, it is desirable to lift the ruffling blade against the action of the spring 53 and to this end the finger 48 overlies the laterally projecting end of a blade-lifting arm 55 adjustably secured upon the usual cloth-presser bar 56, carrying the cloth-presser 57, adapted to be lifted in the usual manner.

An upper ruffling blade 58 is supported by 75 and actuated from shaft 20 by operative connections similar to the described supporting and actuating connections of ruffling blade 47 with shaft 21, with the difference that it projects laterally from its 80 supporting plate in the opposite direction from blade 47, so that it is positioned in direct superposed relation with respect to blade 47, in advance of the needle. By means of the described actuating connections, it is apparent that either or both of the two ruffling blades may be thrown out of operation by shifting the slide-blocks 32 or 36 into alinement with the fulcrum of the 85 crank-arms 12 and 19. Further, while the 90 two ruffling blades in operation are simultaneously advanced and retracted, the movements of each may, by adjustment, be considerably longer than the other and consequently faster, or may be alike as may be 95 desired.

For certain classes of work it would be possible to have the upper ruffling blade operate upon the upper surface of the lower ruffling blade to ruffle a strip of fabric led 100 between the blades, but for rendering the machine capable of a greater variety of products obtained by various adjustments of the actuating mechanism for the ruffling blades, it is desirable to employ an additional element upon which the upper ruffling blade 58 operates to ruffle the material. To this end a separating blade 59 is interposed between the two ruffling blades, being suitably attached to the laterally projecting 110 end of an arm 60 depending from a support 61, adjustably secured by screws as 62 upon a lug 63 projecting from the boss 17. By the provision of this separating blade, the ruffling blades are free to individually perform 115 their functions without interfering with each other.

The lower ruffling blade 47 operates upon a strip of material passing over a separating blade 64 which divides the body garment 120 from the lower ruffled strip. This separating blade 64 is preferably carried by an edge-folding guide 65 for the body-garment mounted on a supporting plate 66 adjustably secured by means of a screw 67 upon 125 the base 1.

In order to effect the product illustrated in Fig. 11 of the drawings, a body-garment *a* is directed to the stitch-forming mechanism by the edge-folding guide 65, an inter-

mediate strip of fabric *b* is led over the lower separating blade 64 and is ruffled by the blade 47, while an upper ply of fabric *c* is led over the upper separating blade 59 where it is acted upon by the upper ruffling blade 58. It is evident that the intermediate ply *b* may extend any distance upon both sides of the needle, but the upper ply *c* is limited at one side by the arm 60 which may serve as an edge-guide, if desired. The product obtained is very pleasing in appearance, for owing to the fact that both ruffling blades operate upon similar sides of the respective fabrics, the ruffles lie in the same direction and may vary in fullness to any desired extent within the limits of adjustment of the actuating mechanism.

Having thus set forth the nature of the invention, what I claim herein is—

1. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, and actuating mechanism for said ruffling blades.

2. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, and means for adjusting said actuating mechanism to vary the extent of movement of said ruffling blades.

3. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, and a guide for a body garment with which the ruffled strips are united by said stitch-forming mechanism.

4. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, and a guide for a body garment with which the ruffled strips are united by the stitch-forming mechanism.

ously ruffling a plurality of plies of fabric independently of each other comprising a plurality of ruffling blades arranged in superposed relation to operate upon the plies of fabric on the same sides of the fabric position, actuating mechanism for said ruffling blades, means for adjusting said actuating mechanism to vary the extent of movement of said ruffling blades relatively to each other, and a guide for a body-garment with which the ruffled strips of fabric are united by the stitch-forming mechanism.

5. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, a separator-blade interposed between the plies of fabrics to be ruffled, and means for supporting said separator-blade.

6. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, a guide for a body-garment, a plurality of blades for separating the several plies of fabric, and supporting means for the separating blades.

7. In a sewing machine, the combination with stitch-forming and cloth-feeding mechanism, of ruffling mechanism for simultaneously ruffling a plurality of plies of fabric independently of each other comprising a plurality of ruffling blades arranged in superposed relation to operate upon the plies of fabric on the same sides of the fabric position, actuating mechanism for said ruffling blades, a blade separating the plies of fabric to be ruffled, and a supporting arm for the separating blade adapted to serve as an edge-guide for one of said plies.

In testimony whereof, I have signed my name to this specification.

CARLYLE W. THOMAS.
